CARL H. BISSELL, OF SYRACUSE, NEW YORK, ASSIGNOR TO CROUSE-HINDS COMPANY,
OF SYRACUSE, NEW YORK, A CORPORATION OF NEW YORK

AUTOMATIC STOP FOR START AND STOP MOTORS

Application filed April 26, 1928. Serial No. 273,019.

This invention relates to motors having a start and stop action and has for its object, a particularly simple and efficient means for stopping the motor to prevent over-run thereof when the coils are deenergized.

The invention consists in the novel features and in the combinations and constructions hereinafter set forth and claimed.

In describing this invention, reference is had to the accompanying drawings in which like characters designate corresponding parts in all the views.

Figures 1 and 2 are opposite side elevations, partly in section of an induction disk motor embodying my invention, Figure 1 being partly broken away and Figure 2 being fragmentary.

Figure 3 is an elevation looking to the left in Figure 1.

Figure 4 is a fragmentary sectional view showing the stop arm and operating means therefor.

This invention comprises a stop to obstruct the rotation of the rotor of the motor and an electro magnetically operated member operated by the field coils or one of them to control the operation of the stop.

I have here shown my invention as embodied in an induction disk motor.

30 1 designates the disk or rotor.

2 are the field coils.

3 are the poles.

4 are shading coils usually provided on the pole pieces.

35 5 is the shaft on which the disk 1 is mounted.

The shaft is supported in any suitable manner on a frame 6 and it is connected through suitable gearing 7 and 8 to a shaft 40 9 connected to the mechanism actuated by the motor. This may be of any mechanism requiring accurate timing particularly as to starting and stopping as for instance, mechanism for controlling street traffic signals,

45 that is, signals where the go signal or green lamp is displayed north and south at a plurality of intersections and the stop or red signals displayed on intersecting streets at the same time, or the green signals on one street at one intersection may alternate with

the red signals on the same street but at the next intersection.

The disk 1 is provided with one or more stop shoulders 10.

11 designates the stop for coating with 55 the stop shoulders to stop the motor, this being here shown as an arm pivoted at 12 to a bracket 13 secured to the base 14 of the frame as by screws 15, the arm being here shown as extending substantially tangential to the 60 disk 1.

In the illustrated embodiment of my invention, the arm is normally arranged in the path of the shoulders 10 although in so far as the stopping operation is concerned, it may 65 but momentarily move into the path of said shoulders and remain there only long enough to engage one of the shoulders and stop the disk 1.

The electro-magnetic means for operating 70 the stop comprises an armature member 16 arranged within the field of one of the coils 2 or pole 3 thereof and in order to be shifted by the electro-magnetic field when the field coil is energized. This member 16 is here 75 shown as an arm pivoted upon the same pivot 12 that the stop arm 11 is mounted. The arm 16 is arranged at an angle to the arm 11 and extends toward the center of the disk in a general radial direction.

80 A spring 18 is coiled about the pivot 12 and anchored at one end at 19 to the base 14 and thrusting at its other end against the stop arm 11. The arms 16 and 11 are connected by suitable means as a yoke 20. The outward movement of the stop arm is limited by a shoulder 21.

85 In operation, when a switch is operated to close the circuit through the coils 2, the disk 1 is actuated and the inductive action of the coils 2 or the pole piece 3 thereof moves the arm 16 outwardly, thus moving the stop arm 11 out of the path of the shoulders 10 where it remains as long as the circuit is closed through the field coils and at the same time 90 tensioning the spring 18. When this circuit is opened, the spring 18 reacts and returns the stop arm 11 with a snap action to its position in the path of the shoulders 10 and 95 stops the rotor so that the synchronism of the 100

mechanism operated by the motor with respect to other similar mechanism is not upset by over-running of the motor.

What I claim is:

- 5 1. The combination of an induction disk motor having a disk rotor and field coils and poles, the disk being provided with a peripheral stop shoulder, a pivoted stop arm extending in a direction tangential to the disk and
10 movable into the path of said shoulder, a pivoted armature member arranged at an angle to the stop arm and normally extending toward the center of the disk and in the field of one of the field coils to be operated
15 thereby to move the stop arm away from the rotor when the field coils are energized and a spring tending to hold the stop arm and the armature arm in their normal positions.
- 20 2. The combination of an electric motor having a rotor, field coils and poles, the rotor having projections thereon, a stop member normally arranged in position to engage the projections on the rotor, an armature element arranged in the magnetic field of one
25 of the field coils to be operated thereby when the field coils are energized, said means being connected to the stop member to shift the same out of its normal position when the field coils are energized to actuate the rotor,
30 and means for returning the stop to engage the projections on the rotor when the coils are deenergized, thereby simultaneously stopping movement of the rotor.
- 35 3. The combination of an electric motor having a rotor, field coils and poles, the rotor having engaging means thereon, a stop member normally coacting with the engagement means on the rotor, an armature element connected with the stop member and magnetically operated by one of the field coils to disengage the stop member when said field coil is energized, and means to return the stop member to engagement with the engaging means on the rotor upon failure of current
40 in the field coil, whereby movement of the rotor is considerably arrested.
- 45 4. The combination of an electric motor having a rotor, field coils and poles, the rotor including a disk having a series of peripheral stop shoulders, a stop member movable into and out of the path of the shoulders, an armature element arranged in the field of one of the coils to be actuated thereby when the field coils are energized to hold the stop element out of the path of the shoulders and to permit the stop element to engage the shoulders upon failure of current in the field coils and thereby instantaneously stop rotation of the rotor.
- 50 60 60. In testimony whereof, I have hereunto signed my name, at Syracuse, in the county of Onondaga and State of New York, this 6 day of April, 1928.

CARL H. BISSELL.
